[57] CLAIM

The ornamental design for a clock, substantially as
shown and described.

DESCRIPTION

FIG. 1 is a front elevation of a clock showing my new
design in which the numerals are arranged in vertical
columns, the rear being substantially plain and unornamented;

FIG. 2 is a perspective view of the clock in FIG. 1
showing the right side and top, the left side and bottom
being mirror images of the right side and top respectively, and

FIG. 3 is a front elevation of another embodiment of my
clock in which the numerals are arranged in horizontal
rows, the rear being substantially plain and unornamented,
the sides being substantially identical to the top
and bottom of the clock in FIGS. 1 and 2, and the top
and bottom being substantially identical to the sides of
the clock in FIGS. 1 and 2.
